UNITED STATES PATENT OFFICE.

JAMES ASA REEDER, OF CORINTH, MISSISSIPPI, ASSIGNOR TO HIMSELF AND
JOSEPH D. OZIER, OF SAME PLACE.

BALING-PRESS.

SPECIFICATION forming part of Letters Patent No. 430,352, dated June 17, 1890.

Application filed November 5, 1889. Serial No. 329,311. (No model.)

To all whom it may concern:

Be it known that I, JAMES ASA REEDER, of Corinth, in the county of Alcorn and State of Mississippi, have invented a new and useful 5 Improvement in Baling-Presses, of which the following is a full, clear, and exact description.

My invention relates to a portable baling-press, preferably employed to compress hay 10 into bales, the object being to provide a simple compact portable baling-press whereon hay or similar material may be baled by pressure from the front or draft end of the press to the rear end, where the compacted bale 15 is tied and discharged.

To this end my invention consists in the provision of mechanical devices whereby a follower will be forced rearwardly through the hay-receiving chamber into the baling-chamber and there retain the compacted bale 20 until it is tied, when the same is discharged through a downwardly-swinging rear door.

My invention further consists in the construction and combination of parts, as is hereinafter set forth and claimed.

Reference is to be had to the accompanying drawings, forming a part of this specification, in which similar letters of reference indicate corresponding parts in all the figures.

30 Figure 1 is a side elevation of the portable baling-press mounted on wheels. Fig. 2 is a partly-sectional top plan view of the device. Fig. 3 is a rear end elevation of the portable press; and Fig. 4 is a detached side elevation 35 of the bale-chamber located at the rear end of the portable press, one side wall being removed to expose a pressed and tied bale therein.

The portable press is mounted on ordinary 40 running-gear of a draft-wagon having suitable strength. On the wagon-bolsters *a* an elongated frame is placed, consisting, partially, of side timbers *A*, that rest on the bolsters, which timbers are suitably connected 45 by transverse pieces, (not shown,) whereon is located a stout plank flooring. At the front end of the flooring mentioned, on each side of the same, the upright posts *b b'* are erected, which are connected by longitudinal cap- 50 pieces *b²* and transverse bars *c*, that together

produce a substantial frame-work *A'* at the front end of the machine for the support of working parts thereon.

At a proper distance from the rear end of the machine on each side thereof two opposite vertical posts *d* are erected on the floor-timbers *A*, which posts are secured from lateral movement and outward displacement by the cross-piece *d'*.

On each side of the bale-press planks *e* are 60 affixed by their ends to the vertical posts *b* and *d*, these planks being spaced apart edge-wise to afford on each side two parallel elongated slots *e'*, in which a follower is guided to reciprocate, as will be further explained. 65

The rectangular space between the side plank walls *e* and the posts *b* and *d* constitutes a hay-receiver or press-box *B*, which is provided with hinged doors *B'*, that join their free edges near the transverse center of the 70 press-box, and when closed may be so retained by the clamping-bars *f*, which are adapted to engage with their depending ends the bracket-loops *f'*, that are affixed to the sides of the press-box *B* near their upper 75 edges.

From the rear end of the press-box *B*, defined by the upright post *d*, an extension of equal width and height is produced, which is represented at *C*. This from its office is termed 80 a "bale-chamber."

The top and bottom walls of the bale-chamber coincide with the planes of the doors *B'* and the floor of the press-box. Preferably this flooring is extended from end to end of 85 the machine. The top wall *g* of the bale-chamber *C* is made secure by any preferred means, and the sides *g'* rendered removable entirely, or they may be hinged to swing open and expose the interior of the chamber. 90 When closed, the sides *g'* are retained from displacement by the vertical exterior standards *h*, that engage a cross-bar *h'* in a manner which will permit their easy detachment.

At the rear end of the bale-chamber *C* a 95 heavy gate or platen *C'* is preferably hinged at the lower exterior edge of the chamber, whereby free access is afforded to this chamber *C* at its rear end. When elevated to close the bale-chamber, the platen *C'* is so 100

retained by hooks i and staple-eyes i' . (See Fig. 1.)

A follower-block D is made to loosely fit in the press-box B, and serves as a movable wall 5 therein. It is retained in a transverse upright position by tongues formed on its side edges of a size to loosely engage the longitudinal slots e' between the side planking of the press-box B, as before mentioned, which 10 engagement of parts will allow the follower-block D to slide from end to end of the press-box when its doors B' are closed and secured.

The means provided for the speedy and forcible longitudinal movement of the follower-block D within the bale-press consists, essentially, of a transverse main shaft E, which is mounted revolutely upon the frame-work A', near its forward edge, to afford room for the rotation of a hand-wheel E', that is secured 20 upon the main shaft near its center of length.

As shown in Fig. 1, the hand-wheel E' is composed of a center hub m and an annular rim m' , the latter being held concentric with the hub and main shaft E by the radial arms 25 m^2 , that are affixed at spaced intervals between the hub and rim and extend beyond the latter to afford hand-holds for the rotation of the wheel and shaft E either toward or from the bale-chamber C. There are an equal number of extension handle-bars m^3 , located by 30 the side of the radial arms m^2 , which by their sliding connection with the guiding-loops m^4 , that secure the ends of the arms m^2 on the rim m' , are rendered susceptible of radial 35 adjustment, whereby leverage for rotary movement of the shaft E may be increased or diminished, as may be required.

Upon the main shaft E, near its ends, which are projected outside of the frame A', the 40 similar spirally-grooved cone-pulleys E² are affixed, said pulleys having their larger ends adjacent to the shaft ends, and their smaller terminals near to the sides of the supporting-frame A'.

45 Near the center of height of the platen C' a rectangular transverse frame C² is secured on said platen and projects beyond its side edges, as shown in Fig. 3. Two vertical partition-blocks n are introduced between and fastened 50 to the horizontal top and lower walls of the frame C² at equal distances from its end walls, which are all provided with circular central perforations that receive and afford revoluble support to the short counter-shafts n' , upon 55 which the mating-sheaves n^2 are secured adjacently in series of three or more, as may be necessary for the effective operation of the press.

The follower-block D is projected outside 60 of the press-box B through the parallel slots e' , formed between the side planking previously mentioned, and has sheave-holding boxes o , produced on these projecting ends, in which two sets of sheaves o' are revolubly 65 supported in manner similar to the mating series of sheaves n^2 on the platen C'.

Upon the cone-pulleys E² stout cords or

traction-ropes F are wrapped, as shown in Fig. 1, said ropes being rove upon the two sets of sheaves n^2 and o' , whereby these parts 70 are connected; hence by a revolution of the main shaft E the follower-block D may be drawn from the front end of the press-box B toward the platen C'.

The traction-ropes F are of equal length, 75 which is proportioned to the length of the entire machine, so that they may be rigged in the following manner: Assuming that the follower-block D is at the rear end of the press-box B, the forward terminal of each 80 traction-rope is attached to the outer end of one of the cone-pulleys E². The ropes F are wrapped around the pulleys toward their inner ends; thence they are rearwardly extended and engage the inner sheaves of the 85 duplicate series of sheaves n^2 on the platen C', and forwardly to pass around the forward sides of the sheaves o' on the follower-block D; thence back and forth, respectively engaging these sheaves until they are all occupied, 90 as shown, when the rear terminal ends of the ropes are secured to the extended ends of the shafts which sustain the sheaves o' .

Near the center of the follower-block D a reversing-rope G is attached, as shown by 95 dotted lines in Figs. 1 and 2, which extends forwardly and is wrapped upon the shaft-body E, the end being secured to the shaft, as is represented in Fig. 2.

When the follower-block D is located at 100 the rear end of the press-box B, there need be but a single turn of the rope G placed on the main shaft E, and thus afford room for the continuous wrapping of said rope thereon, the reversing-rope being removed from contact 105 with the shaft E when the pressing of a bale is being effected.

On the opposite side of the hand-wheel E' a cone-pulley H is mounted and a draft-rope H' is wrapped on it, one terminal r being fastened to the larger end of the pulley. The unwrapped portion of the rope extending forwardly may be manipulated by hand or be attached to the harness of a horse and drawn forwardly to wrap the traction-ropes 115 F on the cone-pulleys they engage, and thus draw the follower-block D rearwardly toward the bale-chamber when a bale is pressed.

In operation the follower-block D is drawn forwardly and forms a front wall for the press-box B. The platen C' is lowered, thus opening the rear end of the bale-chamber C, through which hay is introduced and pushed forward until the press-box and bale-chamber are filled as well as can be effected by hand, any convenient implement being employed to facilitate such an introduction of the material to be pressed. When there has been a sufficient charge introduced, the platen is swung up and secured in place by the hooks i and staples i' . The hand-wheel E' is now revolved toward the front end of the machine, which will wrap the traction-ropes F on the cone-pulleys they engage, and thus forcibly draw the follower- 125 130

block D rearwardly. As the ropes F are withdrawn from the cone-pulleys E² when the follower-block D is moved forwardly, the initial movement of the main shaft E in the direction of the arrow in Fig. 2 will wrap the traction-ropes F upon the larger portions of the cone-pulleys, and consequently move the follower-block at first in a comparatively rapid manner, its speed being gradually diminished as it is drawn rearward, and the resistance of the mass operated upon becomes greater by reason of its compression.

If the machine is operated manually, the handle-bars m⁴ may be extended radially as the operation progresses toward completion, and thus afford increased leverage to condense the hay into a nearly solid bale. When the bale is compressed, each side of the bale-chamber C is removed and the bale-ties s inserted through the grooves s', formed in the faces of the follower-block D and platen C', which ties can be readily adjusted and secured at their ends in the usual manner, the rearward projection of the bale-chamber C facilitating the tying operation by affording free access to the bale before compression is relaxed thereon.

As before indicated, the provision of the outwardly-folding doors B' for the press-box permits this box and its rolling supports to be utilized as a draft-wagon for transportation of any material desired. The doors when opened being inclined against the braces

B² (see Fig. 3) increase the carrying capacity of the press-box, which becomes the body of the wagon when thus adjusted.

Having thus described my invention, what I claim as new, and desire to secure by Letters Patent, is—

The combination, with a portable horizontal press-box, an aligning bale-chamber, a hinged platen which depends when open at the rear edge of the bale-chamber, removable sides for the bale-chamber, a follower-block which is adapted to slide in the press-box and enter the bale-chamber, and upwardly-movable doors for the press-box, of a forwardly-located transverse revoluble main shaft, two grooved cone-pulleys affixed upon the projecting ends of the main shaft, a hand-wheel mounted on the main shaft, mating series of sheave-wheels supported on counter-shafts to revolve at the sides of the platen and follower-block to which they are connected, two traction-ropes which engage the cone-pulleys and sheaves, and a reversing-rope which is connected to the follower-block and main shaft and adapted to draw the follower-block forwardly when the main shaft is turned toward the bale-chamber, substantially as set forth.
